UNITED STATES PATENT OFFICE.

ARNOLD CHRISTIANSON AND CHRISTIAN CHRISTIANSON, OF HAMMOND, INDIANA.

SIDE BEARING.

Application filed December 31, 1926. Serial No. 158,207.

Our invention relates to side bearing structure of the type commonly provided in railway cars between the body and truck bolsters, adjacent to the ends thereof.

5 Our invention has for one of its objects, the provision of an improved and simplified form of side bearing structure.

Another object of our invention is to provide a structure, wherein there is less tendency toward binding of the movable parts 10 against movement than in some of the devices heretofore employed.

Still another object of our invention is to provide a structure, wherein the movable 15 parts are accurately guided and maintained in proper position.

One form which our invention may take 20 is shown in the accompanying drawing, wherein Figure 1 is a plan view of a side bearing structure embodying our invention; Fig. 2 is a view taken on the line 2—2 of Fig. 1; Fig. 3 is a plan view of a blank from which the roller bearing cage of Fig. 1 may be conveniently formed; Fig. 4 is a side 25 elevational view of the bearing cage of Fig. 1, and Fig. 5 is a rear elevational view thereof.

While the structure may be employed in 30 various forms of apparatus, we have, in the present instance, shown it as applied to a body bolster 6 of a railway car body (not shown) and a truck bolster 7 which may be mounted on a railway car truck (not shown) in a usual manner. Upper and lower bearing plates 9 and 10 are secured to the bolsters 35 6 and 7 respectively. Bracket members 11 and 12 are also secured to the bolsters 6 and 7 and are provided with pivot pins 13 and 14, respectively, that extend through slots 40 in the ends of a lever 15. The slots permit free movement of the bolsters 6 and 7 relative to one another in horizontal directions, particularly in cases where there may be a tendency for the distance between the pins 45 13 and 14 to vary, either by reason of the swivelling movement of the truck bolster 7 about the center pin of the truck (not shown) or through relative longitudinal movement as between the bolsters 6 and 7.

50 An anti-friction roller 16 is supported upon the bearing plate 10, in position to be engaged by the bearing plate 9 when the bolster 6 moves down by reason of swaying movement of the car body, or the truck bol-

ster 7 is moved upward, as when the truck 55 wheels (not shown) encounter an elevation in the railroad track.

A cage 17, preferably of pressed metal, is provided for the roller 16, and the roller is pivotally connected thereto by means of 60 a pin or shaft 18. The cage is shown as formed from a metal blank that is illustrated in Fig. 3, on an enlarged scale. This blank is provided with ears or lugs 19 that are bent to upstanding position and are perforated for the reception of the shaft 18. The edges 20 of the blank are turned downwardly and inwardly under the longitudinal edges of the bearing plate 10, and serve 65 as guides for preventing displacement of 70 the roller 16 with respect to the plate 10.

The forward edge of the blank has a tongue-like extension 21 that is bent downwardly, to extend under the lever 15, and has a hole that is in vertical alinement with a hole in the lever 15. A link 22 is disposed above the lever 15 and is connected thereto by a pin 23 which extends through the link 22, the lever 15, and the extension 21. The rear end of the link is disposed above a perforation 24 in the cage 17 and has a portion 75 25 which extends downwardly therethrough and is upset at its lower end. The portion 25 is offset at 26 and is provided with a flange or rib 27 by means of which it is rigidly secured in the cage. The cage 17 thus has, in effect, a double connection with the lever 15—one through the tongue 21, and another through the link 22—so that 80 there will be a balanced pull exerted upon 90 the pin 23 and the cage 17 by the lever 15.

It will be seen that as the bolsters 6 and 7 are moved relatively to one another in a horizontally transverse direction, such movement will be imparted to the cage 17 and the roller 16, so that the roller is automatically and positively moved along the bearing plate 10 into position to properly receive impacts from the bearing plate 9. The lever 15 and its points of connection to the pins 13 and 14 are on a line parallel to the axis of the shaft 18, so that there is little or no binding resistance to the movement of the lever and the roller.

The bracket 11 is secured to the bolster 105 6 at a point between the inner end of the roller 16 and the center of the bolster, so that there will be a smaller degree of verti-

cal movement of said bracket with respect to the bolster 7 than if the bracket were placed adjacent to the outer or higher end of the bolster 6, for the reason that the bolster 6 will rock, with the car body, in a vertical plane. It will also be seen that the roller 16 is constantly in engagement with the bottom bearing plate 10 and that the guide flanges 20 of the cage 17 co-operate with the edges of this normally stationary plate, so that the cage 17 normally has no vertical movement relative to its associated plate, as would be the case if it were suspended from the plate 9. In the latter instance, lost motion between the cage and the plate would be taken up whenever the roller was brought into engagement with the bottom plate.

We claim as our invention:—

- 20 1. The combination with a railway car having a body bolster and a truck bolster,

of a bracket extending downwardly from the body bolster, a bracket extending upwardly from the truck bolster, a lever pivotally connected at its ends to said brackets, 25 a roller bearing cage disposed between said brackets, and a pivotal connection between the forward end of said cage and the mid portion of said lever, the lever being disposed exteriorly of the cage.

2. Bearing structure comprising a roller, a pressed metal cage for said roller, the said cage comprising ears struck up from the body portion of a plate, downturned flanges at the sides of said plate, and a tongue projecting from one end of the plate for attachment to a lever or the like.

In testimony whereof we the said ARNOLD CHRISTIANSON and CHRISTIAN CHRISTIANSON have hereunto set our hands.

ARNOLD CHRISTIANSON.
